UNITED STATES PATENT OFFICE.

HARRY C. BIERMAN AND ARTHUR J. BASTIAN, OF WILKINSBURG, PENNSYLVANIA,
ASSIGNORS TO WESTINGHOUSE ELECTRIC AND MANUFACTURING COMPANY, A
CORPORATION OF PENNSYLVANIA.

GEAR BLANK.

Application filed September 28, 1923. Serial No. 665,374.

Our invention relates to composite articles, more especially to composite gear wheels embodying a fibrous material and the well known phenolic condensation products, formed integrally with a metal center or supporting hub member as by molding under heat and pressure.

It is among the objects of our invention to provide a composite gear wheel of the above designated character which shall be of simple inexpensive construction, which shall be economical to manufacture with a minimum amount of waste material resulting therefrom, which shall be readily adapted to manufacture in relatively large quantities with uniform results and which shall be mechanically durable and efficient as a gear element when embodied in machine tools, engines or the like.

Composite gear wheels comprising a non-metallic rim portion of fibrous material and a hardened binder mounted or molded on a metal center or hub support as heretofore manufactured, were formed of a plurality of superposed layers of fibrous sheet material such as duck, which is a heavy woven textile fabric, or paper which was suitably treated by impregnating with a binder such as a phenolic condensation product and assembled in segment or ring form about a metal center or hub in the matrix of a suitable mold. The necessity for punching segments and rings resulting in a considerable amount of scrap material averaging approximately 30% of the total material utilized in the gear wheel. Another more recent development consisted of winding a continuous strip of fibrous material edge-wise about the periphery of the hub member such strip being cut or notched to provide the proper curvature due to the variation in the lengths of the outer periphery of the gear element and the outer periphery of the supporting hub member.

Our present invention is directed to a method of winding fibrous strips about the periphery of the hub in such a manner as to eliminate crimping of the material and to reduce the amount of waste produced by the notching of the strip to a minimum. To this end we employ suitable notches of such proportions as to produce a gear wheel of uniform density throughout its non-metallic rim portion after the final molding

operation. We further propose employing a double strip which facilitates the notching operation and the assembling or winding of the strip on the hub.

In the accompanying drawings constituting a part hereof and in which like reference characters designate like parts:

Fig. 1 is an elevational view of a gear wheel embodying the principles of our invention,

Fig. 2 is an elevational view of a strip of fibrous material notched and partially doubled which is employed in the gear wheel illustrated in Fig. 1,

Fig. 3 is a plan view of a notched strip split at one end and

Fig. 4 is a plan view of a single strip adapted to be wound around a hub member as illustrated in Fig. 1.

Referring to Fig. 1, a composite gear wheel, such as we propose, comprises a metal center or hub 1 having an annular opening 2 adapted to be mounted on a suitable drive shaft (not shown). The hub is provided with a central extending hub portion 3, a web portion 4 having openings 5 therein for the purpose of lightening the structure and an outer rim 6 provided with a knurled periphery 7, the knurl being preferably of the diamond-shape type, but may comprise a square knurl or simply grooves. An outer non-metallic rim portion 8 in which the teeth are cut is formed on the hub member 1 by molding a plurality of superposed layers of fibrous sheet material treated with a suitable binder such as a phenolic condensation product thereon.

We prefer to utilize a strip 9, Fig. 4, having V-shape notches 10 therein which extend from one edge of the strip transversely across leaving just sufficient material between the bottom of the V and the edge of the strip to provide sufficient strength of the body portion to facilitate handling the material for winding it around the hub 1. The strip 9 is wound around the outer periphery of the hub 1 with the notched edge adjacent to the knurl to form a continuous helix of superposed layers. After winding the strips on the hub the edges of the notches 10 are in contact, thus compensating for the difference in the diameters of the periphery of the hub 1 and the outer edge of the wound strip 9. The assembled

structure is then placed in a suitable mold and subjected to heat and pressure to compact the fibrous material and to consolidate the mass, thereby forming a non-metallic 5 rim portion 8 as an integral part of the hub 1.

In place of the strip 9, Fig. 4, we may utilize a wider strip 11, Figs. 2 and 3 and by forming substantially diamond-shape 10 notches 12 centrally therein, the strip may be folded upon itself to form a double strip portion 13, Fig. 2, which may be wound on a hub member similarly to the strip 9 with a wide portion of the notch adjacent to the 15 knurl 7. If for any reason it is desirable to utilize a single strip 9, it is possible to employ a wide strip 11 having diamond-shape notches 12 therein, folding the strip and splitting the same along its longitudinal center 14, as it is being wound on the hub. This splitting may be accomplished in various ways, as by a single knife-edge provided in the guide which may be in proximity to the hub member as the strip is wound there- 20 on, or a circular knife-cutter may be employed.

It is evident from the above description of our invention that gear wheels formed in accordance therewith are of uniform density 25 and of a homogeneous structure throughout the non-metallic body portion, and that the process employed for forming the same is adapted to facilitate production and to minimize the waste. The notching of the 30 strip material may be accomplished in various ways as by punching dies or rotary cutters and this operation may be made a part of the winding operation as the strip may be passed through such dies or cutters as it 35 is being wound on the hub.

Although we have described a specific embodiment of our invention, it will be obvious to those skilled in the art that various modifications may be made in the details of construction without departing from the principles herein set forth. For instance, the 40 notches in the strip may be of any suitable proportions relative to the width of such

strip and the density and texture thereof and the angular spacing of the notches may 50 be varied with varying diameters of the hub member so as to entirely eliminate buckling or crimping of the fibrous material.

We claim as our invention:—

1. A composite article comprising a metal 55 hub and a non-metallic rim, said rim comprising a helical strip of fibrous sheet material folded at its center and notched on the folded edge which is disposed adjacent the hub and consolidated with a binder. 60

2. A composite article comprising a metal hub and a non-metallic rim, said rim comprising a helical strip of fibrous sheet material folded at its center and provided with substantially V-shaped notches and consolidated with a binder. 65

3. A composite article comprising a metal hub and a non-metallic rim, said rim comprising a helical strip of fibrous sheet material folded at its center and notched on 70 the folded side only and consolidated with a binder.

4. A composite article comprising a metal hub and a non-metallic rim, said rim comprising a folded strip of fibrous sheet material in the form of an endless helix having notches extending transversely thereof and substantially across its entire face on its folded side only, said rim being consolidated with a hardened binder. 75 80

5. A composite article comprising a metal hub and a non-metallic rim, said rim comprising a helix of fibrous sheet material in the form of an endless strip, said strip having diamond-shaped openings extending 85 transversely thereof and folded lengthwise to provide a folded edge having V-shape notches which are disposed adjacent to the hub, said rim being consolidated with a hardened binder. 90

In testimony whereof, we have hereunto subscribed our names this 25th day of September, 1923.

HARRY C. BIERMAN.
ARTHUR J. BASTIAN.
